Design No. 12,719, dated January 31, 1882.

UNITED STATES PATENT OFFICE.

OLIVER B. KEELEY, OF SPRING CITY, PENNSYLVANIA.

DESIGN FOR A HEATING-STOVE.

SPECIFICATION forming part of Design No. 12,719, dated January 31, 1882.

Application filed December 19, 1881. Term of patent 7 years.

To all whom it may concern:

Be it known that I, OLIVER B. KEELEY, a citizen of the United States, and a resident of Spring City, Chester county, Pennsylvania, have invented a Design for Heating-Stoves, of which the following is a specification.

My design is fully shown in the accompanying drawing.

The stove comprises the hot-air drum A, the magazine-section B, illuminating-section D, fire-pot section E, ash-pit section F, base G, division-rings H, and rear-flue casing J.

The hot-air drum A has panels *a*, ornamented as shown, and an ogee base with ornamentation in accord with that of the panels *a*.

The magazine-section B is divided into a series of segments by columns *b*, each comprising a base, an ornamented shaft, and a capital. Each of the segments of the section B has a central panel, *d*, and a line-work border.

The illuminating-section D has mica doors *e* and sliding shields *f*, and the fire-pot section E also has illuminating-doors.

The ash-pit section F has the usual dampered openings in front, and on each side has a segment, *g*, ornamented as shown.

The base G has a skirting, *h*, cast with the feet *i*, the ornamentation of the feet and skirting being uniform in character.

The division-rings H of the stove have their lower edges waved or scalloped; and the casting of the flues at the rear of the stove is divided into four parts, *m*, *m'*, *m''*, and *m'''*, each ornamented as shown.

I claim—

1. The design for the hot-air drum A, said design comprising panels *a* and the ogee base, all ornamented as shown and described. 35

2. The design for the magazine-section B, said design comprising segments separated by the ornamented columns *b*, as shown and described. 40

3. The design for the magazine-section B, said design comprising segments separated by the ornamented columns *b*, and each having a central panel, *d*, as shown and described. 45

4. The design for the ash-pit section F, said design comprising the dampered openings in front and the ornamented segments *g*, as shown and described. 50

5. The design for the base G, said design comprising the skirting *h* and feet *i*, ornamented as shown and described.

6. The design for the flue-casing J, comprising the sections *m*, *m'*, *m''*, and *m'''*, ornamented as shown and described. 55

7. The design for the complete stove, comprising the hot-air drum A, sections B, D, E, and F, base G, division-rings H, and flue-casing J, all ornamented as shown and described. 60

In testimony whereof I have signed my name to this specification in the presence of two subscribing witnesses.

OLIVER B. KEELEY.

Witnesses:

W.M. S. ESSICK,
GEO. W. FLOYD.
